CLAIM

The ornamental design for a mesh shoe organizer, as shown and described.

DESCRIPTION

FIG. 1 is a front perspective view of the mesh shoe organizer; FIG. 2 is a left side elevational view of the mesh shoe organizer of FIG. 1; and,

FIG. 3 is a front elevational view of the mesh shoe organizer of FIG. 1; and,

FIG. 4 is a bottom plan view of the mesh shoe organizer of FIG. 1.

The broken lines shown in the drawings form no part of the claimed design. The right side elevational view of the claimed design is a mirror image of FIG. 2. The rear elevational view of the claimed design is a mirror image of FIG. 3. The top plan view of the claimed design is a mirror image of FIG. 4.
